UNITED STATES PATENT OFFICE

95,055

DESIGN FOR AN AUTOMOBILE BROADCASTING TRUCK

George P. MacDonald, Great Neck, N. Y., assignor to Richfield Oil Corporation of New York, New York, N. Y.

Application October 15, 1934, Serial No. 53,622

Term of patent 7 years

To all whom it may concern:

Be it known that I, George P. MacDonald, a citizen of the United States, residing at No. 117 Overlook Avenue, in the county of Nassau and State of New York, have invented a new, original, and ornamental Design for Automobile Broadcasting Truck, of which the following is a specification, reference being had to the accompanying drawing, forming part thereof.

mobile broadcasting truck, showing my new design.

Figure 2 is a rear view of the automobile broadcasting truck shown to a slightly reduced scale and the tractor shown in dotted lines in Figure 1 has been omitted.

I claim:

The ornamental design for an automobile broadcasting truck as shown and described.

GEORGE P. MACDONALD.
